(57) **CLAIM**

The ornamental design for a protective HVAC duct cover, as shown and described.

DESCRIPTION

FIG. 1 is a perspective view of a protective HVAC duct cover showing my new design;

FIG. 2 is a top plan view thereof, the bottom plan view being the same;

FIG. 3 is a right side elevational view thereof;

FIG. 4 is a left side elevational view thereof;

FIG. 5 is a top end view thereof; and,

FIG. 6 is a bottom end view thereof.

The drawings are lined for the color orange which form a part of the claimed design.
